UNITED STATES PATENT OFFICE

OSCAR TERVO, OF QUINCY, MASSACHUSETTS, ASSIGNOR TO WILFRED B. MATHEWSON,
OF NORTH WEYMOUTH, MASSACHUSETTS

GREASE DISPENSER

Application filed February 6, 1930. Serial No. 426,236.

This invention relates to grease dispensers of that type comprising a container for holding grease and a pump within the container and by which the grease is dispensed therefrom. Such devices are commonly used in garages, filling stations and the like for supplying grease or lubricant to the transmissions, differentials and other parts of automobiles.

10 In the operation of such a grease dispenser it is highly desirable that indication should be given when the grease or lubricant is substantially exhausted from the container for when substantial exhaustion of the grease or lubricant occurs the pump will not function properly and will not deliver a full supply of grease due to the fact that the grease is not freely delivered to the inlet of the pump.

15 I have by my present invention provided a novel means for giving indication when the grease is substantially exhausted from the pump, such indication being in the form of a lock or stop which arrests the action of the pump. I have also provided means whereby this lock or stop is automatically released when the container is refilled with grease or lubricant so that as soon as it has been thus refilled the dispenser is in condition to be operated.

20 In order to give an understanding of the invention I have illustrated in the drawings a selected embodiment thereof which will now be described after which the novel features will be pointed out in the appended claims.

25 Fig. 1 is a vertical section through a grease dispenser embodying my invention;

Fig. 2 is a fragmentary section on the line 2—2, Fig. 1;

30 Fig. 3 is a section similar to Fig. 2 but showing the cap or closure removed for refilling the container;

Fig. 4 is a section on the line 4—4, Fig. 5;

Fig. 5 is a fragmentary sectional view 35 through the operating shaft.

40 In the drawings 1 indicates a container adapted to contain grease, lubricant or similar material, said container being in the form of a cylindrical drum having an opening 2 in one end. Situated within the con-

tainer is a pump 3 which may be of any suitable type but will preferably be in the nature of a gear pump. This pump has an inlet opening 4 and the discharge is connected to a discharge pipe 5 which extends through 55 the wall of the container and communicates with a delivery pipe which may be flexible if desired, this being a common construction.

45 In the device herein shown the pump is operated through a vertically-extending shaft 6 which is actuated from a crank handle 7 situated outside of the container. This crank handle is shown as fast on a shaft 8 which carries at one end a bevel gear 9 that meshes with another bevel gear 10 on the upper end of the shaft 6. The shaft 8 and gears are housed in a closure or cover member 11 which may be applied to the top of the container 1 and which closes the opening 2, said closure being retained in position by 60 suitable clamping screws 12, of which only one is shown.

50 As stated above one feature of my invention relates to a novel means for giving the operator indication when the grease or lubricant is nearly exhausted from the container, such indication being given by the automatic arresting of the operation of the pump, and as further stated above, another feature of the invention relates to a construction by which the pump is freed for operation when the container is refilled.

55 The operating shaft 6 is a sectional shaft, it comprising the upper section 13 on which the gear 10 is mounted, the tubular section 14 and the lower section 15 which extends into the gear pump 3 and to which one of the gears is secured. The shaft section 13 is square in cross section and the tubular section 14 is also square in cross section. The lower end of the shaft 13 fits into the upper end of the tubular section 14 and these two sections are secured together by means of a pin 16.

60 The lower end of the tubular section 14 telescopes over the shaft section 15 which is round throughout most of its length but which is provided with a square head 17 at its upper end that fits within the square tubular section 14.

18 is a spring enclosed within the tubular section and confined between the section 13 and the head 17.

Slidably mounted on the tubular section 14 is a float member 19, the latter having a square opening through which the square section 14 extends so that said float member is compelled to rotate with the shaft but is capable of having a sliding motion longitudinally thereof.

Rigid with the float member 19 is a blade member 20 which is shaped so that as it is rotated by the shaft when the latter is operating the pump, said blade tends to force the grease downwardly toward the pump inlet 4, the purpose of the blade being to ensure that a proper supply of grease is always maintained at the inlet end of the pump.

The gear 10 at the upper end of the shaft section 13 is provided with a square opening to receive said shaft and it is withdrawable from the shaft when the cover plate 11 is removed.

The shaft section is provided with a pin 21 with which the hub of the gear 10 engages when the cover 11 is in place and the gear is assembled with the shaft as shown in Fig. 1, and when the parts are in this position the shaft is in its lowered position and the spring 18 is somewhat compressed, the lower end of the sleeve 14 coming nearly to the top of the pump casing. This is the position of the parts when the device is in use and so long as there is a quantity of grease or lubricant in the container 1, as for instance if the level of the grease therein was such as indicated by the dotted line 22, the buoyant quality of the float 19, which in such case would be immersed in the grease, would tend to cause the float to rise, and would maintain the float against the pin 16 by which the shaft sections 13 and 14 are connected. This position of the float is further ensured by the operation of the blade 20 for whenever the pump is operated the rotative movement of the shaft 6 is transmitted to the blade 20 and as the blade is moved in the grease mass it tends to force the grease downwardly and the reaction on the blade tends to force the blade upwardly. This blade thus not only serves to agitate the grease but also serves to feed it toward the pump inlet.

As the grease is dispensed from the container and the level of the grease therein falls below the float 19 and blade 20 then the float and blade will descend with the falling grease level and will gradually approach the dotted line position in Fig. 1.

Means are provided whereby when the grease or lubricant has become so far exhausted from the container as to make it likely that the grease or lubricant will not be properly fed to the pump inlet the action of the pump will be automatically arrested and this is accomplished by providing a stop

finger 24 on the inside of the container 1 which is situated to be engaged by one end of the blade 20 as the latter rotates when said blade has descended into substantially the dotted line position Fig. 1.

Since the blade is rigid with the float and the float is arranged to rotate with the shaft 6 the engagement of the blade with the finger 21 will arrest the rotation of the shaft and thus stop the operation of the pump. When this occurs the container is ready to be refilled and the refilling operation is accomplished by removing the cover 11 with the operating gears, it being understood that the gear 10 is readily withdrawable from the upper end of the shaft 13, and then introducing a fresh supply of grease or lubricant through the opening 2.

Means are provided whereby when the cover 11 is removed the pump will be automatically released or freed for operation and this is accomplished through the action of the spring 18.

It will be remembered that so long as the cover 11 is in place the shaft section 13 is held depressed and the spring 18 is consequently compressed. When the cover 11 is removed together with the gear 10 the spring 18 expands and lifts the shaft section 2 upwardly as shown in Fig. 3.

Since the tubular shaft section 14 is connected to the shaft section 13 said tubular section will partake of this spring-impelled upward movement and the tubular section 14 will be forced up through the blade and float. The upward movement of the shaft is limited by one or more screws 25 that are screw threaded through the lower end of the tubular section 14 as shown in Fig. 4 and the points 26 of which project into the tubular section somewhat and are thus in a position to engage the under side of the head 17. The engagement of these screws with the head 17 of the shaft section 15 limits the upward spring-impelled movement of the shaft sections 13 and 14. During the latter part of this upward movement the heads of the screws 25 engage the center portion of the blade 20 and thus raise the blade and float from the dotted line position Fig. 1 to the full line position Fig. 3. This upward movement of the blade frees it from the stop finger 24 and thus releases the pump shaft for further operation.

After the desired amount of grease or lubricant has been deposited in the container 1 then the cover 11 may be replaced, in doing which the gear 10 will be inserted over the upper end of the shaft section 13. The engagement of the hub of the gear with the pin 21 will depress the shaft section and thus compress the spring 18. During the downward movement of this shaft section it will be forced through the float member and blade leaving them in their elevated posi-

tion as shown in full lines Fig. 1, which position they maintain until the grease or lubricant in the container again approaches exhaustion.

5 With this device, therefore, the action of the pump will be arrested before the grease in the container has been exhausted to the point where it will not be properly fed to the pump inlet and the operation of refilling the container will automatically release the pump thus placing it again in condition for further operation.

I claim:

15 1. In a grease dispenser, the combination with a container open at the top, of a pump therein for dispensing grease therefrom, a removable closure for the top, pump-operating mechanism carried thereby, means for automatically arresting the operation of the pump when the grease in the container approaches exhaustion, and means for rendering the last-named means inoperative when the closure is removed.

25 2. In a grease dispenser, the combination with a container open at the top, of a pump therein, a removable closure for the top, pump-operating mechanism carried thereby, an agitating blade operating simultaneously with the pump, means for automatically arresting the movement of said blade and thus stopping the pump when the grease in the container approaches exhaustion, and means to release the blade from the blade-arresting means when the closure is removed.

35 3. In a grease dispenser, the combination with a container open at the top, of a pump therein, a removable closure for the top, pump-operating mechanism carried thereby, means for automatically arresting the operation of the pump when the grease in the container approaches exhaustion, a spring normally tending to release the pump, which spring is held inoperative by the closure when the latter is in its operative position.

45 4. In a grease dispenser, the combination with a container open at the top, of a pump therein, a removable closure for the top, pump-operating mechanism carried by the closure, an agitating blade connected to the pump-operating mechanism and adapted to agitate the grease and force the latter toward the pump inlet, stop means to arrest the movement of said blade when the grease in the container approaches exhaustion, and a spring normally held inoperative by the closure when it is in place but operating automatically when the closure is removed to release the blade from the stop means.

55 60 5. In a grease dispenser, the combination with a container open at the top, of a pump in the container for dispensing grease therefrom, a removable closure for the top, pump-operating mechanism carried by said closure, stop means operative to arrest the operation

of the pump when the grease in the container approaches exhaustion, and a spring operative when the closure is removed to render said stop means inoperative.

65 In testimony whereof, I have signed my name to this specification.

OSCAR TERVO.
